UNITED STATES PATENT OFFICE.

JOHN A. CHAPMAN, OF BIGELOW, ARKANSAS.

ATTACHMENT FOR CAR-STEPS.

1,129,956.

Specification of Letters Patent.

Patented Mar. 2, 1915.

Application filed June 3, 1914. Serial No. 842,739.

To all whom it may concern:

Be it known that I, JOHN A. CHAPMAN, a citizen of the United States, residing at Bigelow, in the county of Perry and State of Arkansas, have invented certain new and useful Improvements in Attachments for Car-Steps, of which the following is a specification, reference being had to the accompanying drawings.

10 This invention relates to new and useful improvements in attachments for car steps and more particularly to what will be hereinafter known as an extension car step, the main object of the present invention being 15 the provision of a movable step which can be quickly and easily lowered when passengers are getting off or on the train and, at the same time can be quickly returned to its inoperative position, when not in use.

20 Another object of the present invention is the provision of an extension car step of the above character which will possess advantages in points of efficiency and durability, is inexpensive to manufacture and, at the 25 same time, is simple in construction and operation.

With the above and other objects in view, the invention consists in the novel features of construction, combination and arrangement of parts as will be hereinafter referred to and more particularly pointed out in the specification and claims.

In the accompanying drawing forming a part of this application, Figure 1 is a perspective view of an extension car step, illustrating the manner of operating the same. Fig. 2 is a transverse sectional view. Fig. 3 is a section taken on the line 3-3, Fig. 2. Fig. 4 is a top plan view of the step member; 40 and Fig. 5 is a transverse sectional view, the operating parts thereof being eliminated.

Referring more particularly to the drawing, 1 indicates the car platform and extending downwardly from the end thereof are the usual stationary car steps 2. Arranged directly beneath the lower one of the steps 2, is a movable step member 3 which is supported by means of the movable bars 4, the lower ends of which are disposed horizontally, as shown at 5 and secured to the underside of the step member 3. The upper ends of the bars 4 are slidably mounted within the channel bars 6 which are secured to the underside of the steps, said channel members 55 being preferably rectangular in form and having an elongated slot 7 formed therein,

in which the brace rods 8 are adapted to work.

The rods 8 are secured at one end to the bars 4, while the other ends thereof are secured to the bolts 9 which are adapted to work within the slots 10 formed in the actuating arms 11, said arms having enlarged end portions which are provided with transverse openings to receive the supporting 65 shaft 12. The arms 11 are secured to the shaft 12 by means of the set screws 13, so that the arms will move with the rotation of the shaft.

The shaft 12 is supported beneath the 70 platform 1 by means of the vertical bars 14, the upper ends of which are disposed at right angles and secured to the under face of the platform. Mounted upon one end of the shaft 12, is an arm 15, one end of which is securely held in place by means of the set screw 16 which connects the arm to the shaft so that the arm will be actuated upon the rotation of the shaft. The other end of the 75 arm is provided with a plurality of openings 17 and adapted to be removably arranged within said openings, is a bolt 18 which is carried by one end of the connecting bar 19, the other end of said bar being pivotally connected to the lower end of the 80 actuating lever 20.

The actuating lever 20 is pivotally mounted upon the platform 1 and is provided with a spring actuated pawl 21 which is adapted to engage the rack bar 22 and retain the 90 movable step member 3 in a raised or lowered position. In order that the step may be readily returned to its normal position, I provide the coil springs 23, one of the ends of which is secured to the lower face of the 95 platform 1 while the lower ends thereof are secured to the arms 11, at the inner ends of the slots 10. From this it will be apparent that upon the release of the lever 20, the tension of the coil springs 23 will return the 100 step member 3 to its normal or raised position.

From the above description taken in connection with the accompanying drawing, it will be apparent that I have provided a 105 simple and durable extension step which can be readily applied to any make of passenger car in use and which can be quickly lowered when the passengers are ascending or descending the steps, thus doing away 110 with the usual stool or portable step in use at the present time. It will also be apparent

that I have provided a device of the above character which is extremely simple in its construction and at the same time can be manufactured and placed upon the market at a comparatively low cost.

While I have shown and described the preferred form of my invention, it will be obvious that various changes in the details of construction and in the proportions may 13 be resorted to for successfully carrying my invention into practice, without sacrificing any of the novel features or departing from the scope of the appended claims.

While I have shown and described the device as constructed for manual operation, it 15 will be apparent that the device may be slightly altered so that compressed air may be utilized for operating the device or any other source of power such as electricity, 20 which is carried by the train upon which the device is used.

Having thus described this invention, what I claim is:

1. An extension step for cars and other 25 vehicles, comprising parallel guide bars adapted to be secured to the under side of the permanent steps of a car, and formed on their under sides with longitudinal slots; bars slidably located in the first named bars 30 and provided at their lower extremity with an auxiliary step; parallel vertical bars adapted to be secured to the under side of a car platform and having a horizontal shaft journaled therein; longitudinally slotted

arms mounted upon the said shaft and secured thereto by set screws; rearwardly disposed arms secured to said shaft by set screws; a link bar pivoted to the rear end of said arms and to the lower extremity of a vertically disposed vibrative lever; 40 brace rods secured at their front ends to the step carrying bars through the slots in the guide bars and at their rear ends to bolts adapted to move within the slotted arms; and brace rods also secured at one end 45 to the traveling bolts and at the other end to the step carrying bars and at an angle to the first named brace bars, whereby through the vibration of the operating lever the auxiliary step may be raised or lowered. 50

2. In an extension step such as described, comprising step carrying bars, slidably mounted in slotted guide bars and with brace rods extending from the step carrying bars to bolts slidably mounted in slotted arms secured to an operating shaft, connected by suitable means to a vibrative lever; coil springs having one end connected with the slotted arms and the opposite end connected to the shaft support whereby the auxiliary step may be automatically raised as hereinbefore set forth. 55

In testimony whereof I hereunto affix my signature in the presence of two witnesses.

JOHN A. CHAPMAN.

Witnesses:

W. E. GLASCO,
W. E. LIVELY.
